Atty.

UNITED STATES PATENT OFFICE.

GUSTAF SELANDER, OF CHICAGO, ILLINOIS.

CLINKER-EXTRACTOR.

1,353,428.

Specification of Letters Patent. Patented Sept. 21, 1920.

Application filed September 22, 1919. Serial No. 325,287.

To all whom it may concern:

Be it known that I, GUSTAF SELANDER, a citizen of the United States of America, and a resident of Chicago, in the county of Cook, State of Illinois, have invented certain new and useful Improvements in Clinker-Extractors, of which the following is a specification.

This invention relates to a hand implement for withdrawing clinkers from the fire pots of stoves and furnaces, and has for its object,

To provide a simple and efficient structural formation and association of parts in which the carrying shank of a clinker engaging claw is connected in a pivotal and longitudinally adjustable manner to an ordinary poker rod to coact with the same in the clinker withdrawal operation, the said clinker engaging claw when not required for use being adapted to be moved back on the poker rod so as not to interfere with the ordinary use of such poker rod, all as will hereinafter more fully appear.

25 In the accompanying drawing:—

Figure 1, is a perspective view illustrating the implement parts in an open condition ready for engagement with a clinker to be removed.

30 Fig. 2, is a side elevation showing the parts in a retracted and inactive position.

Fig. 3, is an elevation of the underside of the implement.

Like reference numerals indicate like 35 parts in the several views.

Referring to the drawing, 1 designates an ordinary poker rod, having at one end a suitable point 2 and at the other end an operating hand grip 3.

40 4 designates a pair of radius links pivoted at one of their ends to the sides of the poker rod 1 adjacent to the hand grip 3, with the other of their ends having pivotal connection with the carrying rail of the 45 clinker engaging head or claw, now to be described.

50 5 designates the movable clinker engaging head or claw above referred to, preferably of a plate formation and having marginal inturned flanges 6 as shown. Said head or claw is adapted for coöperation with the poker rod adjacent to its point 2, and to such end is carried and supported by means 55 as follows.

55 7 designates a carrying rail pivotally connected at one end to swinging ends of the radius links 4, and fixedly attached at its

other end to the head or claw 5 aforesaid. In the present invention the carrying rail 7 is of a concavo-convex or channel form in 60 cross-section, so that in either of its herein-after described positions it will fit snugly to the round shank of the poker rod 1, and be held from lateral play or movement.

8 designates an offset in the carrying rail 65 7 adjacent to the point of attachment of said bar to the radius links 4, and adapted to provide a convenient hand grip in the action of clamping and holding a clinker between a side of the poker rod 1 and the 70 head or claw 5 during a clinker extracting operation.

With the present construction, the clinker engaging claw 5 when not required for use is moved back out of the way on the poker 75 rod 1, with the connecting radius links 4 swung back in a position next to the hand grip 3 as illustrated in Figs. 2 and 3. When required for use the clinker engaging head or claw 5, is moved forward into operative 80 relation to the point portion of the poker rod 1, by a semi-circular swinging movement of the radius links 4, as illustrated in Fig. 1.

Having thus fully described my said invention, what I claim as new and desire to secure by Letters Patent, is:—

1. A clinker extractor comprising, a poker rod having a handle at one end and a clinker engaging formation at the other 90 end, a radius link pivoted to said rod near the handle end thereof, a carrying rail pivoted at one end to said link, the said carrying rail having a concavo-convex form in cross section adapting the same for straddling engagement with the poker rod, and a clinker engaging claw attached to the free end of said carrying rail.

2. A clinker extractor comprising, a poker rod having a handle at one end and a 100 clinker engaging formation at the other end, a pair of radius links pivoted to the poker rod near the handle end and at opposite sides of said rod, a carrying rail pivoted at one end between said links, the said carrying rail having a concavo-convex form in cross section adapting the same for straddling engagement with the poker rod, and a clinker engaging claw attached to the free end of said carrying rail.

Signed at Chicago, Illinois, this 20th day of September, 1919.

GUSTAF SELANDER.
